COMBINATION FIELD DESK AND TRUNK

Alexander C. Weiss, Takoma Park, Md., assignor
to the United States of America as represented
by the Secretary of the Army

Application January 28, 1952, Serial No. 18,259

Term of patent 3½ years

(Cl. D87—5)

To all whom it may concern:

Be it known that I, Alexander C. Weiss, a citizen
of the United States, residing at Takoma Park,
in the county of Montgomery and State of
Maryland, have invented a new, original, and
ornamental Design for a Combination Field Desk
and Trunk, of which the following is a specification,
reference being had to the accompanying
drawings, forming a part thereof.

Figure 1 is a perspective view of the combination
field desk and trunk, showing the same set
up as a desk; and

Figure 2 is a like view on a reduced scale, showing
the device closed.

The essential features of the invention are
shown in full lines.

I claim:

The ornamental design for a combination field
desk and trunk, substantially as shown and de-
scribed.

ALEXANDER C. WEISS.
